[57] CLAIM

The ornamental design for an ankle collar for footwear, as shown and described.

DESCRIPTION

FIG. 1 is a lateral side elevational view of an ankle collar for footwear showing my new design;

FIG. 2 is a rear elevation thereof;

FIG. 3 is a top plan view thereof;

FIG. 4 is a front elevation thereof;

FIG. 5 is a bottom plan view thereof;

FIG. 6 is a lateral side elevational view of an ankle collar for footwear showing a second embodiment of my new design; and,

FIG. 7 is a rear elevation of the second embodiment. The broken line showing of a shoe is for illustrative purposes only and forms no part of the claimed design.
